(57) **CLAIM**

I claim the ornamental design for a bottle dock, as shown and described.

DESCRIPTION

FIG. 1 is a top perspective view of a bottle dock, showing my new design.

FIG. 2 is a front view of the bottle dock.

FIG. 3 is a rear view of the bottle dock.

FIG. 4 is a left side view of the bottle dock.

FIG. 5 is a right side view of the bottle dock.

FIG. 6 is a top view of the bottle dock; and,

FIG. 7 is a bottom view of the bottle dock.

(Continued)

The broken lines are shown for the purpose of illustrating parts of the article that form no part of the claimed design.
